Primary Examiner—Brian N. Vinson*Attorney, Agent, or Firm*—Merchant, Gould, Smith, Edell, Welter & Schmidt, P.A.[57] CLAIM

The ornamental design for a bathroom fixture, as shown and described.

DESCRIPTION

FIG. 1 is a top, rear, and right side perspective view of a first embodiment of a bathroom fixture showing my new design;

1 Claim, 7 Drawing SheetsFIG. 2 is a top plan view thereof, the bottom being a mirror image of that shown;

FIG. 3 is a front elevational view thereof;

FIG. 4 is a rear elevational view thereof;

FIG. 5 is a left side elevational view thereof;

FIG. 6 is a reduced front perspective view of a second embodiment thereof, the only difference from the first embodiment being the addition of an identical second fixture, with the broken-line disclosure of a shelf being for illustrative purposes only and forming no part of the claimed design;

FIG. 7 is a reduced front elevational view of the first embodiment thereof, with the broken-line disclosure of a towel ring being for illustrative purposes only and forming no part of the claimed design;

FIG. 8 is a reduced front perspective view of the second embodiment thereof, with the broken-line disclosure of a combination cup and toothbrush holder being for illustrative purposes only and forming no part of the claimed design;

FIG. 9 is a reduced front perspective view of the second embodiment thereof, with the broken-line disclosure of a toilet roll spnidle being for illustrative purposes only and forming no part of the claimed design; and,

FIG. 10 is a reduced front perspective view of the second embodiment thereof, with the broken-line disclosure of a soap dish being for illustrative purposes only and forming no part of the claimed design.
